SWITCHING CASE FOR ELECTRIC POCKET LAMPS

Emile Venot, Marseilles, France; vested in the Alien Property Custodian

Application October 8, 1940, Serial No. 369,215
In France November 24, 1939

2 Claims. (Cl. 240—10.65)

Actually and in a general way, it is known of disposing on one side of the case of an electric pocket lamp, a switch which may operate to effect lighting or extinction of the lamp.

This switch is provided with an indispensable finger piece always jutting out from the case. Now, experience sufficiently proved that this conventional type of switch offers certain inconveniences, the principal of which are, first, a certain difficulty of moving the cut-out requiring very often for this operation, owing to a little stiffness in the working of the switch, the use of both hands, one, to hold the case, the other to move the switch; then, the jutting out of the finger piece or button of the switch, is a cause of hooking other objects being in the same pocket of the dress containing the lamp, which also may be the cause of trouble, and finally the adjustment of the contact strip of the battery engaging the interruptor, each time the battery is replaced.

Those risks and principal inconveniences are now suppressed by the object of the present invention, consisting essentially of a casing of an electric pocket lamp a part of which is movable with the precise aim of constituting a switch without any control device jutting out, placed in the electric circuit feeding the lamp.

This casing is characterised by the fact that the electric lamp is movable and that its bottom constitutes at the same time, owing to the lamp being movable, a sliding contact on one of the conducting blades of the battery and a thrust block limiting its movement by meeting the other likewise conducting blade. This meeting of the blades with the lamp base effects lighting of the lamp due to the movement of said thrust block and removal of the latter effects extinction of the lamp.

The switching casing for an electric pocket lamp is shown on the accompanying drawing, serving as an example of a practical embodiment of one of the forms of the invention.

Thus in the drawing

Fig. 1, essentially schematic, shows the principle of the invention itself.

Fig. 2 is a view from the front, with parts cut off, in order to make comprehension easier, of a practical embodiment of the switching case.

Fig. 3 is a view from the side, likewise with parts cut off, of the switching case shown on Fig. 2.

Fig. 4 shows the same switching case seen on plan.

Considering Fig. 1 schematic, it is noticed that

a lamp 1 is fixed by known means, in preference by screwing, on a support 2. This support is movable, consequently it may be moved longitudinally and alternately following the direction of the arrows A and B, and that the lowest part of the bottom 3 bearing contact element 4 of lamp 1 is always in contact with a blade 5, flexible and current conducting, connected with one of the poles of an electric source, 6, while base 3 itself is in contact with a blade 7, likewise a conductor, connected also with the electric battery 6 and forming the other pole.

It is obvious that in this position, the electric circuit is closed upon the connections of lamp 1 and that this latter will light. But if support 2 is pushed in the direction of arrow A, position shown by a dotted line, it immediately will result that base 3 leaving its contact with blade 7 will be cut off the electric circuit, and by this fact lamp 1 will be extinguished. That is the principle and the working of the switching case, a practical embodiment of which is shown in Figs. 2, 3, 4.

In this practical embodiment, casing 3 and support 2 of lamp 1 are more favorably constituted of moulded and insulating materials or of wood. Support 2 slides inside case 3, position shown in dotted line in Figs. 2 and 4, guided by slots 9 of convenient shape, more particularly visible in Fig. 3, which permits displacement longitudinally and by sliding of lamp base 3 and its point 4 to contact with blade 5 conductor of battery 6, and to come likewise in contact with blade 7 according to the principle of the invention, already described and shown in Fig. 1.

To change the battery 6, when exhausted, and the lens 10 removed from support 2, battery 6 is easily removed and replaced. A reversal of these operations will of course bring the switching casing back into operative condition.

The switching casing contributes a progress in this kind of appliances by avoiding use of the conventional type of switch and of the inconveniences thereof, and produces likewise a new result in allowing conveniently handled pocket lamps, since lighting and extinction of these lamps may now be performed in an easy manner, with a single hand. However, the shapes, the sizes of parts and the materials used for the manufacturing of this switching casing may vary without changing the general principles of the herein described invention.

What I claim and desire to secure by Letters Patent of the United States is:

1. In a flash light having a casing for a lamp battery, a slidable cover for one end of said casing made of insulating material and having a recess with an aperture for receiving an electric lamp, and means for holding said lamp in a position adjacent the end of said battery to maintain sliding contact between the end of the lamp base and one contact of said battery and allow sliding of the cover along said end until the side of said base meets the second con-

tact on said battery which serves as a stop therefor, said slidable cover being exposed upon the major portion of the surface of the outer sides and ends as well as on the top thereof.

5. 2. A flashlight according to claim 1, having the length of the cover substantially equal to the maximum width of the casing so as to form a continuation thereof in idle position thereof and to project at one end a distance beyond the 10 side of said casing in illuminated closed circuit condition of the lamp thereon.

EMILE VENOT.
